UNITED STATES PATENT OFFICE.

KARL WEISS, OF MEISSEN, GERMANY.

DRYING APPARATUS.

991,679.

Specification of Letters Patent.

Patented May 9, 1911.

Application filed June 1, 1910. Serial No. 564,368.

To all whom it may concern.

Be it known that I, KARL WEISS, a subject of the German Empire, residing at Meissen, Germany, have invented certain new and useful Improvements in Drying Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a trough-shaped drying apparatus, comprising a rotatable perforated body, used for drying potatoes, adhesive masses and the like, the heating medium, *e. g.*, hot air or furnace gases, being introduced into the inner chamber and the material to be dried being distributed over the outer periphery of the drum.

20 The invention consists in arranging an agitator or mixing device over the perforated body which constantly disintegrates and uniformly distributes the material over the perforated body and effectively prevents the perforations being stopped up, as was frequently the case heretofore, by material settling firmly on the perforated body.

25 One illustrative embodiment of the invention is represented by way of example in the accompanying drawing, wherein:

30 Figure 1 is a vertical, longitudinal section and Fig. 2 a vertical transverse section showing the drying apparatus.

35 Referring to the drawing, a revoluble cylinder *b* provided with small perforations is arranged in the stationary trough *k* which is covered by a top-piece or cover *a* and, if desired, can be heated specially, said cylinder being provided on its periphery with blades *c* arranged at intervals, their broad ends passing in close proximity to the trough *k* to effectually scrape from the trough any adhering material. These blades are placed close together there being only sufficient space for the passage of rotating arms *e*.

40 A rotatable shaft *d* which is provided with arms *e* moving between the blades *c* and whose speed of rotation is greater than that of the cylinder *b*, passes through the top chamber inclosed by the cover *a*. The arms *e* of this agitator or stirrer are placed 45 slantwise or provided with bent lateral edges

in order to feed the material along the periphery of the drum.

The wet material is supplied at one end of the drying apparatus preferably by one or more screw conveyers *f* at a constant speed. The heating medium is supplied at the opposite end of the drying apparatus, in the illustrative embodiment through the hollow journals *b'* of the perforated cylinder *b*, hot air or furnace gases serving as the heating medium which is blown by a fan into the rotating cylinder *b*. The dried material leaves the apparatus through the outlet *g* provided in the trough, it being thrown out by the blades of the rotating cylinder which are opposite the outlet *g*, while the air or gases saturated with water issue through the outlet *h*.

When the cylinder *b* rotates, the blades arranged on the periphery thereof lift the material to the top part of the drying apparatus where it is distributed by the arms of the shaft *d* over the periphery of the cylinder and is consequently rapidly dried. In consequence of the exterior periphery of the perforated cylinder being constantly influenced by the arms of the agitator, the material to be dried is prevented from becoming fixed on the drum, so that the stoppage of the perforations which frequently occurred heretofore, particularly in the case of certain materials, is effectively prevented.

I claim:

1. In a drying apparatus of the character described the combination with a trough, of a perforated cylinder, broad blades mounted on the cylinder whose ends pass in close proximity to the trough to scrape adhering material therefrom, and an agitator rotatably mounted over the cylinder and having arms passing between said blades to scrape the cylinder and progress the material.

2. In a drying apparatus of the character described the combination with a trough having an inlet and an outlet, and a cover having outlets for the material treated and the heating medium of a perforated cylinder, closely arranged blades on the periphery thereof whose ends pass in close proximity to the trough wall to scrape any material therefrom, and an agitator revoluble in said cover and having arms movable between the blades in close proximity thereto and to the cylinder to scrape the cylinder and progress the material.

3. In a drying apparatus the combination with a trough, of a foraminous cylinder mounted therein having an enlarged hollow trunnion for the admission of a drying medium, cover having an outlet at one side for the material treated and for the drying medium at its top, closely arranged spaced blades on the cylinder whose ends pass in close proximity to the trough, wall, and an 5 agitator in the cover between the outlet for the drying medium and one end of the 10

cover having agitator arms adapted to pass between the blades and in close proximity to the cylinder to scrape the cylinder and progress the material toward its outlet.

15

In testimony that I claim the foregoing as my invention, I have signed my name in presence of two subscribing witnesses.

KARL WEISS.
